UNITED STATES PATENT OFFICE.

MICHAEL J. GLENNON, OF SUMMIT, AND HARRY G. HIGHAM, OF MURRAY HILL, NEW JERSEY.

MEANS FOR INSTRUCTING GOLF STROKES.

Application filed April 9, 1927. Serial No. 182,273.

This invention relates, generally, to a device for instructing and training the user in the correct form of making strokes with golf clubs.

The invention has reference, more particularly, to a simple unitary structure adapted to serve as a guide to the user whereby the latter is aided to properly address a golf ball with a playing club, and caused to correctly swing the club through a proper arc or path of movement to produce correct form in play, and whereby the user is habituated to proper muscular movements of the arms and body through which correct form in play is attained. To this end the novel instruction device of this invention comprises a simple unitary structure in the form of a suitable base plate upon which is mounted a pair of laterally spaced guide members positioned to demark or bound the proper path of movement to be taken by the golf club when swung to strike the ball; said guide-members being so shaped as not to interfere with the proper movements of the club, but being calculated to obstruct improper movements thereof; at the same time said guide members are preferably made of resilient material, such as molded rubber, so that, should they be engaged by the club, the same will not be injured, nor will contact therewith unpleasantly shock or jar the player. The device is also constructed to provide sighting elements which are calculated to train the vision of the player in following the path the stroke of the club should properly describe.

Other objects of this invention, not at this time more particularly enumerated, will be clearly understood from the following detailed description of the same.

The invention is clearly illustrated in the accompanying drawings, in which:—

Figure 1 is a perspective view illustrating the novel instruction device of this invention as used by a player; Figure 2 is a plan view of the novel instruction device; Figure 3 is a transverse section, taken on line 3—3 in Figure 2; and Figure 4 is a side elevation of the novel instruction device.

Similar characters of reference are employed in all of the hereinabove described views, to indicate corresponding parts.

As illustrated in the drawings, the novel instruction device comprises a flat base member 6. This base member 6 may be of any

desired peripheral shape but is preferably rectangular, and of a length somewhat in excess of its width. The base member 6 may be made of any suitable material, such as wood, fibre, rubber, etc.

Fixed on said base member so as to extend rearwardly from the forward end thereof are a pair of upstanding guide shoulders 7 and 8, the same being laterally spaced apart for a distance somewhat in excess of the length of a golf-club head, thus bounding and defining a club-head guideway 9. The arrangement of said guide shoulders 7 and 8 is such that they incline outwardly, in their longitudinal dimension or direction, relative to that side or edge of the base member which is opposed to the player when the device is in use, thereby defining a club-head guideway 9 which inclines away from the player toward its outer end, all for purposes which will be subsequently more fully explained. Said guide shoulders 7 and 8 are curved upwardly and outwardly from their lower inner side portions toward their upper outer side portions, as indicated at 10. The inner end portions of said guide shoulders are also outwardly curved as at 11, to provide a flaring entrance mouth leading into the guideway 9. The upper face of the base member 5 within the guideway 9 and midway between the guide shoulders 7 and 8 is provided with sighting marks 12, which are preferably in the form of painted or otherwise produced spots of a color sharply contrasting with the color of the base. These sighting marks 12 are spaced apart and are aligned to the proper direction of club head movement through the guideway and between the guide shoulders 7 and 8. The center sighting mark 12 may also serve as a positioning spot for properly placing or locating the golf ball within the guideway 9 ready to be addressed by the club of the player. It will be obvious that the sighting marks may take forms other than the circular form shown in the drawings, and even may be constituted by a continuous line should it be so desired.

Preferably the guide shoulders 7 and 8 are made of molded rubber, which material is by reason of its shock absorbing ability is best adapted for the purpose, since should either one or the other of the guide shoulders 7 and 8 be inadvertently struck with the golf club, when the latter is swung by the

player, no shock or jar of any consequence is transmitted to the player, likelihood of injury to the club is avoided, and the guide shoulders themselves will wear better since 5 the rubber long withstands repeated blows without appreciable injury.

In making up my novel instruction device, I may furnish the same with a base of rigid material and guide shoulders of rubber, or, 10 if desired, the base may also be made of rubber, with which the rubber guide shoulders may be combined either as an integral structure or in suitable mechanical attachment to the base. 15 In making use of my novel instruction device, the same is placed before the player in the manner illustrated in Figure 1. A golf-ball 13 is spotted or positioned within the guideway 9, and the player equipped 20 with the golf-club 14 having a suitable club-head 15. The player takes his stance facing that longitudinal side of the base member 5 which will position the rearward entrance mouth of the guideway 9 to the player's 25 right. When the device and player are thus positioned the guideway 9 will incline in a forward direction, i. e. in a direction corresponding to the direction of movement of the club when the latter is swung by the 30 player, slightly away from the player, thus compelling the latter to finish the stroke with the desired slightly outward movement of the club, and thereby guarding the player against committing the fault of "pulling his 35 stroke". In addressing the golf-ball, the player is aided in visualizing the proper path of swing through which the club should be directed both by the bounding guide shoulders 7 and 8 and by the sighting marks 40 12. The player in making the stroke strives to pass the club-head 15 into the guideway 9, into contact with the ball 13, and then out of the guideway 9, without permitting the club to engage said guide-shoulders 7 or 8. Should 45 the club head strike or graze either guide shoulder 7 or 8, the player is instantly made aware that the stroke was not properly directed. If after engaging the ball the player's club strikes the guide-shoulder 8 before 50 clearing the guideway, he is instantly made aware that he is pulling his stroke. Experiencing these warnings the player will repeatedly practice the stroke with the aid of the instruction device until he attains that 55 proficiency which enables him to successfully strike the ball without contacting either at the beginning or the end of the stroke with either one or the other of said guide shoulders. Not only is my novel instruction

device adapted to serve as an aid to the user in perfecting his playing stroke, but it also aids him in judging the proper stance, particularly with reference to the distance thereof from the ball to be addressed, for if the player takes his stance too close to the ball he will notice a tendency to strike the outlying guide shoulder 7 during the performance of the stroke, and, on the other hand, should he take his stance too far from the ball he will notice a tendency to strike the nearer guide shoulder 8. Warnings are thus given which enable the player to better judge his distance, and thus easily acquire the habit of correct stance.

From the brief description of the construction and manner of using our novel instruction device it will be clearly understood that the same provides in a very simple and unitary form a device well calculated to aid the user in perfecting golf club strokes. We are aware, however, that some changes could be made in the above described embodiment of our invention without departing from the scope thereof as defined in the appended claims, it is therefore intended that all matter contained in the above description or shown in the accompanying drawings shall be interpreted as illustrative and not in a limiting sense.

Having thus described our invention, we claim:—

1. A device for the instruction of golf strokes, comprising a base member, and a pair of laterally spaced longitudinally extending upstanding guide shoulders on said base adapted to define a guideway for the free passage of the head of a properly swung golf-club, and within which the ball to be addressed may be placed, said guide shoulders and the guideway defined thereby being inclined outwardly relative to the side of the base-member opposite which the user takes position.

2. A golf stroke instruction device as defined in claim 1, in which said guide shoulders are made of soft rubber.

3. A golf stroke instruction device as defined in claim 1, in which said guide shoulders are outwardly curved from their lower inner sides to their upper outer sides, and in which the inner rearward end portions of the same are laterally and outwardly curved.

In testimony that we claim the invention set forth above we have hereunto set our hands this 5th day of April, 1927.

MICHAEL J. GLENNON.
HARRY G. HIGHAM.
